UNITED STATES PATENT OFFICE.

HUGO GREBEHEM, OF HERBSLEBEN, GERMANY.

SAFETY DEVICE FOR PREVENTING RAILWAY ACCIDENTS.

Application filed March 24, 1927, Serial No. 178,081, and in Germany June 30, 1926.

This invention relates to an automatic safety device for preventing a train overrunning the signal: "line blocked" in foggy weather or for any other reasons, and thereby affording an absolutely reliable protection against railway accidents. The essence of the invention consists in the provision of means by which with pulled signal: "line blocked" the compressed-air brakes of the train are automatically operated and thus the train stopped.

The accompanying drawing illustrates the improved safety-device by way of example: Fig. 1 is an edge view of the same partly in section, Fig. 2 is a side view of the same, and Fig. 3 shows a detail of Fig. 1 on a larger scale.

One of the locomotive wheels of a train is fitted on its outer side with a fixed concentric metal rim *a*, which is provided with a plurality of radial borings, in each of which a bolt *b* is located and acted-upon by a strong spiral spring *c* in such a way that it normally projects somewhat from the outer periphery of the rim *a*. In a recess *d* of the rim *a* provided beside each boring therein, a horizontal lever arm *e* is located so as to bear with its free inner end by action of a spring *g* upon the inner end of said bolt, while its outer end is pivoted to a radial lever *f*, which at its other slot-guided end is connected with a valve-plug *h* adapted to shut-off a steam pipe *i* in one of its end positions. All said steam pipes *i* are at their inner ends in communication with a common closed central cap *k* to which a steam supply pipe *n* is attached. Within said cap *k* a closed bush *k*¹ is located, into which lead the inner ends of two pipes *l*. The outer ends of all said steam pipes *i* and of said pipes *l* lead into a circular pipe *m* located on the inner periphery of the rim *a* and allowing a free circulation of the steam therethrough and a separate function of each single bolt *b*.

On the outside of the permanent railway line, a metal bar *o* with declined ends *o*¹ is so adjustably arranged that with pulled signal: "line blocked" it is placed within the path of and in level with the outer periphery of said rim *a* and then adapted to func-

tion as hereinafter described. While with "free line" signal it is moved beyond reach of said rim and then does not act upon the same.

The operation with pulled signal: "line blocked" and corresponding adjustment of the bar *o* is as follows:

All the bolts *b* are by said bar *o* successively forced inwards against the action of their springs *c*, whereby the levers *e*, *f* are so moved that the valves *h* are opened and steam supplied through pipe *n* is allowed to flow from the cap *k* through the pipes *i* to the circular pipe *m* and hence through the pipes *l* into the closed bush *k*¹, from which a pipe *n*¹ leads to the compressed-air brakes of the train, the latter being thereby stopped.

The bolts *b* after having passed over the bar *o* return by action of their springs *c* to their initial position, while for returning also the valves *h* into the latter position first the steam supply through the pipe *n* must be stopped by the conductor of the locomotive, whereupon the levers *e*, *f* with the valves *h* are moved back by action of their springs *g*.

What I claim is:

A safety-device for preventing trains overrunning the signal: "line blocked," comprising, in combination, a fixed rim on the outer side of one of the locomotive wheels of a train having radial borings therein, spring-pressed bolts in said borings adapted to normally project somewhat from the outer periphery of said rim, spring-pressed linked levers at one end in contact with the inner ends of said bolts, valves in connection with the other slot-guided ends of said levers, a steam supply pipe system leading to the compressed-air brakes of the train and normally shut-off by said valves, and an adjustable bar with declined ends on the permanent railway line placed with pulled signal: "line blocked" within the path of and in level with the outer periphery of said rim and then adapted to operate said bolts and thereby to open said valves and to free the steam supply therethrough.

In testimony whereof I have hereunto set my hand.

HUGO GREBEHEM.
